Primary Examiner — Ian Simmons*Assistant Examiner* — Keith Frank(74) Attorney, Agent, or Firm — Stetina Brunda Garred and Brucker; Mark B. Garred(57) CLAIM

The ornamental design for a container for cosmetic products, as shown and described.

DESCRIPTION

FIG. 1 is a top perspective view of the container for cosmetic products of the present invention showing my new design; FIG. 2 is a front view thereof, the broken lines in the drawing forming no part of the claimed design;

FIG. 3 is a rear view thereof, the broken lines in the drawing forming no part of the claimed design;

FIG. 4 is a left side view thereof, the broken lines in the drawing forming no part of the claimed design;

FIG. 5 is a right side view thereof, the broken lines in the drawing forming no part of the claimed design; and,

FIG. 6 is a top view thereof.
